UNITED STATES PATENT OFFICE.

JOHN HENRY TRISMEN, OF NEW YORK, N. Y.

PASTING-MACHINE.

No. 857,423.

Specification of Letters Patent.

Patented June 18, 1907.

Application filed February 14, 1907. Serial No. 357,343.

To all whom it may concern:

Be it known that I, JOHN HENRY TRISMEN, a citizen of the United States, and a resident of the city of New York, Port Richmond, borough of Richmond, county of Richmond, and State of New York, have invented a new and Improved Pasting-Machine, of which the following is a full, clear, and exact description.

10 The object of the invention is to provide a new and improved pasting machine, more especially designed for pasting sheets of tissue paper or other material together to form ornaments, such as bells, festoons, lamp shades and like articles, the arrangement being such that a large number of sheets can be quickly and accurately fastened together without the employment of skilled labor.

15 The invention consists of novel features 20 and parts and combinations of the same, which will be more fully described hereinafter and then pointed out in the claims.

A practical embodiment of the invention is represented in the accompanying drawings 25 forming a part of this specification, in which similar characters of reference indicate corresponding parts in all the views.

Figure 1 is a plan view of the improvement; Fig. 2 is a sectional side elevation of 30 the same on the line 2—2 of Fig. 1, and showing the pasting devices, in pasting position; Fig. 3 is a transverse section of the same on the line 3—3 of Fig. 1, and showing the pasting devices in a raised non-pasting position; Fig. 4 is a plan view of a sheet showing the 35 paste as applied by one of the pasting devices, and Fig. 5 is a like view of another sheet, showing the paste as applied by the second pasting device.

40 A number of trays or like supports A, A', A², A³ are adapted to support the sheets B of paper or other material adapted to be pasted together, as hereinafter more fully described, and the said supports are attached to a table C mounted to turn on a central hollow pin D, held on a plate D' connected by posts D² with a base E fastened to the floor or other foundation. As illustrated in the drawings, the supports A and A² are located diametrically 45 opposite each other and at right angles to the supports A', A³ likewise disposed diametrically opposite each other. The supports A, A', A², A³ are adapted to pass successively under the oppositely arranged paste boxes F 50 and F', adapted to contain paste or a like ad-

hesive substance, and the said paste boxes are provided in their bottoms with sets of apertures F² disposed according to a predetermined design, that is, according to the configuration of the article to be produced. 60 The paste boxes F and F' are attached to a cross bar F³ secured to the upper end of the pin D, so as to hold the paste boxes in the desired position above a pair of oppositely disposed supports A, A² or A', A³.

65 Into the paste boxes F and F' extend sets of plungers G and G' registering with the apertures F² and adapted to pass through the same and carry along sufficient paste at their bottoms, and to deposit this paste onto 70 the uppermost sheet B in the corresponding supports A, A² or A', A³. The sets of plungers G, G' are secured at their upper ends, and outside of the paste boxes F, F', to cross heads G², G³ connected with each other 75 by a cross bar H adapted to be moved up and down, so as to lift the sets of plungers G, G' sufficiently high that their bottoms pass above the apertures F², to allow the thick 80 paste to pass into and through the apertures F². It is understood that the paste is sufficiently thick not to pass or drop out of the apertures F², but when the plungers G, G' are moved downward they carry along a 85 thin disk of the paste contained in each aperture, and this thin disk of paste is delivered by the plunger to the top of the sheets B supported on the corresponding supports A, A² or A', A³, respectively. Now, by reference 90 to the drawings, it will be seen that when the supports A', A³ are in pasting position under the paste boxes F, F', then the other two supports A, A² are in position for receiving each a sheet B by an operator seated in front 95 of the corresponding supports A, A². Now when the table C at the next operation is given a quarter turn, then the supports A, A² pass into pasting position under the paste boxes F, F', while the supports A', A³ pass into a sheet-receiving position, that is, pass 100 in front of the operators, to permit the latter to place a new sheet on top of the uppermost sheet already in position on the said supports and in contact with the paste previously deposited on the uppermost sheet by the sets of 105 plungers G, G'.

In order to impart the desired up and down sliding motion to the plunger G, G', the following arrangement is made: The cross heads G², G³ are mounted to slide on guide 110

pins F^4 , F^5 attached to the paste boxes F and F' , respectively, and the said cross heads G^2 are connected with each other by a cross bar H provided with downwardly extending rods H' mounted to slide in bearings F^6 attached to or formed on the cross bar F^3 previously referred to. On the lower ends of the rods H' are journaled friction rollers H^2 traveling on an annular cam I secured to or formed on top of the table C , so that when a quarter turn is given to the table C then the friction rollers H^2 travel up the inclines of the cam I , and when the quarter position is reached, then the friction rollers H^2 drop off the upper ends of the inclines back into the lowermost position. Now during the upward traveling of the friction rollers H^2 on the inclines of the cam I , the rods H' , bar H and cross heads G^2 , G^3 are lifted to raise the 15 plunger G to the position shown in Fig. 3, and when the friction rollers H^2 drop downward then the plunger G , G' pass in a like direction, and in doing so, carry some of the paste down onto the sheets B held on the corresponding set of supports A , A^2 or A' , A^3 .

In order to give a preliminary raising to the sets of plunger G , G' after they have deposited the paste onto the sheets B , to allow turning the table C , the following arrangement is made: The cross bar H is engaged by the reduced upper end J' of a rod J , mounted to slide in the hollow pin D and engaged at its lower end by a treadle K under the control of one of the operators seated in front of one of the supports, as shown in Fig. 1, the support A^2 . Now when the operator presses the treadle K , the rod J is lifted and with it the cross bar H and the sets of plunger G , G' , to raise the latter sufficiently high above the sheets B and the supports A , A^2 or A' , A^3 , to allow convenient turning of the table C without the supports striking against the lower ends of the plunger G , G' . After a quarter turn is given to the table C , the latter is locked automatically in place, and for this purpose a locking bolt L is provided (see Fig. 2), mounted to slide in a suitable bearing arranged on the plate D' and adapted to engage a recess or a keeper C' formed in the under side of the table C . A spring L' arranged in a casing D^3 presses the bolt L so as to snap the latter into engagement with the recess C' , whenever the table C reaches the end of its turning position. The casing D^3 is preferably formed or secured to the under side of the plate D' , as plainly indicated in Fig. 2. The lower end of the bolt L is engaged by one end of a lever N fulcrumed on the plate D' and adapted to be engaged at its other end by a collar J^2 secured on the rod J , so that when the operator presses the treadle K and thereby lifts the rod J then the collar J^2 imparts a swinging motion to the lever N , whereby the locking bolt L is pulled downward and consequently with-

drawn from the recess or keeper C' , to unlock the table C and to allow turning of the same for the purpose previously described.

The sets of plunger G , G' may be arranged in such a manner that one set applies paste to the sheets B near the outer edges thereof, while the other set applies paste to the sheets at or near the centers thereof, so that the sheets pasted readily form easily opening ornaments such as bells, festoons, lamp shades and the like.

It is understood that the sheets B , after being pasted together, are stamped or cut out to give the desired shape to the connected sheets, as indicated in dotted lines in Figs. 4 and 5, so that several ornaments are produced from one set of connected sheets B.

In using the device, the operators on opposite sides of the machine place single sheets on top of the previous one on the corresponding supports A , A^2 or A' , A^3 , and then the operator presses the treadle K to unlock the table C and to raise the plunger G and G' out of engagement with the sheets and free of the corresponding supports. The operator then gives a quarter turn to the table C and releases the treadle K , so that the plunger G , G' are raised and then drop, to carry the paste to the sheets B on the corresponding supports, and while this takes place, the operators again place the sheets B on the sheets held on the supports in front of them, after which the above described operation is repeated. Now it is evident that whenever a support comes in front of an operator it contains a sheet provided on its top surface with paste, and consequently when the new sheet is placed on top of the pasted one, then the two sheets are united. As any desired number of such sheets are placed successively one on top of the other and placed together in the manner described, it is evident that a large number of such sheets can be readily pasted in a comparatively short time.

Although I have described the table C as intermittently turned by hand, it is evident that suitable mechanism may be provided for turning the table C intermittently by power.

Having thus described my invention, I claim as new and desire to secure by Letters Patent:

1. A pasting machine provided with a paste box for containing paste, and having its bottom provided with an aperture, a cross head above the said paste box, and provided with a plunger extending into the said box and registering with the aperture, a plurality of supports for the sheets to be pasted, a table on which the supports are carried, said table being adapted to pass the supports successively into pasting position under the said paste box, for the plunger to deliver the paste to the sheet, and means whereby the movement of the table may elevate the plunger to 130

raise the lower end of the same into the paste and to permit the supports to pass under the bottom of the plunger.

2. A pasting machine provided with a paste box for containing paste and having its bottom provided with an aperture, a cross head above the said paste box and provided with a plunger extending into the said paste box and registering with the said aperture, a 5 revoluble table having a plurality of supports for the sheets to be pasted together, the said supports being adapted to pass successively into pasting position under the said paste box, and means controlled by the said table 10 for raising and lowering the said cross head. 15

3. A pasting machine provided with a paste box for containing paste and having its bottom provided with an aperture, a cross head above the said paste box and provided 20 with a plunger extending into the said paste box and registering with the said aperture, a revoluble table having a plurality of supports for the sheets to be pasted together, the said supports being adapted to pass successively 25 into pasting position, means controlled by the said table for raising and lowering the said cross head, and a locking device for locking the table in place as soon as a support moves into pasting position. 30

4. A pasting machine provided with a paste box for containing paste and having its bottom provided with an aperture, a cross head above the said paste box and provided with a plunger extending into the said paste 35 box and registering with the said aperture, a revoluble table having a plurality of supports for the sheets to be pasted together, the said supports being adapted to pass successively into pasting position under the said paste 40 box, a cam on the said table, and a slide mounted to slide up and down and connected at its upper end with the said cross head, and provided at its lower end with a friction roller for engagement with the said cam. 45

5. A pasting machine provided with a

paste box for containing paste and having its bottom provided with an aperture, a cross head above the said paste box and provided with a plunger extending into the said paste box and registering with the said aperture, a 50 revoluble table having a plurality of supports for the sheets to be pasted together, the said supports being adapted to pass successively into pasting position under the said paste box, a cam on the said table, a slide mounted 55 to slide up and down and connected at its upper end with the said cross head, and provided at its lower end with a friction roller for engagement with the said cam, and a manually controlled locking device for locking 60 and interlocking the said table. 65

6. A pasting machine comprising a pair of oppositely disposed paste boxes, each having apertures in its bottom, sets of plungers for the said paste boxes and registering with the 70 corresponding apertures, and a table mounted to turn and having a plurality of supports, of which two are at a time in pasting position under the said paste boxes, and the other two are in sheet receiving position between the 75 said paste boxes. 80

7. A pasting machine comprising a pair of oppositely disposed paste boxes, each having apertures in its bottom, sets of plungers for the said paste boxes and registering with the 75 corresponding apertures, a table mounted to turn and having a plurality of supports, of which two are at a time in pasting position under the said paste boxes, and the other two are in sheet receiving position between the 80 said paste boxes, and means controlled by the said table for raising and lowering the said sets of plungers on turning the table. 85

In testimony whereof I have signed my name to this specification in the presence of two subscribing witnesses.

JOHN HENRY TRISMEN.
